IRONER WITH STEAMING ATTACHMENT

John J. Getgey, Cincinnati, Ohio, assignor to
 Empire Ironer, Inc., Cincinnati, Ohio, a corpora-
 tion of Ohio

Application April 22, 1943, Serial No. 484,013

3 Claims. (Cl. 38—14)

This invention relates to power driven ironers and is particularly concerned with a construction in which steam is applied to the clothes being ironed continuously during the course of the ironing operation. The invention has general application to any type of power driven ironer which utilizes a rotatable feed roll and an ironing shoe. Because of the neatness and compactness of the structure of the invention due to the arrangement and configuration of the parts, it may be said to have a particular application to ironers intended for home use.

It has long been recognized in all types of ironing that clothes can be ironed smoother, more evenly, and with less danger of scorching if they are slightly moistened at the time of the ironing contact. For this reason, it has always been conventional to moisten the clothes to be ironed in a batch prior to the commencement of the operation.

Where the moistening is done by hand or under any circumstances where it is a batch operation, it is impossible to impart to all portions of all of the clothes an equal degree of moistening. Some portions may become slightly saturated to a point where they remain wet after the article has been ironed, while others may lack moisture to a point where they will not iron evenly and may become scorched during the operation. In addition, the batch of clothes tends to become dried out during the course of ironing and, if there are interruptions to the work, this tendency may increase to a point where it is necessary either to remoisten the batch or to iron the clothes while they are insufficiently moistened.

To remedy the difficulties and inconveniences resulting from conditions such as those described, it has been the concept of the present invention to moisten the clothes being ironed by means of the application of steam over the entire surface area of each article, and to apply the steam simultaneously with the ironing operation. In this way, the necessity for hand moistening is completely avoided and it is never necessary for the ironer operator, such as a housewife, to determine the extent of moistening prior to the commencement of the ironing. Since the clothes may be inserted into the ironer in perfectly dry condition, through the utilization of the improvement of this invention it is entirely possible to iron a batch of clothes evenly and well regardless of interruption. Each article ironed will be moistened to the exact degree desired throughout the ironing operation.

Among the other objects of the invention, it

has been the purpose of the inventor to provide an ironing shoe which is adapted to moisten clothes by the use of steam simultaneously as they are ironed and to distribute the steam evenly over the clothes in such a way that the most delicate fabrics may be ironed evenly and smoothly and without fear of scorching.

Another object has been to provide, as an element of an ironer, an ironing shoe in which the heating element, conventional in the ordinary electrically operated ironer, is utilized to convert to steam water placed in a closed jacket, which jacket is an integral part of the shoe.

Another object has been to provide in an ironer shoe a steam jacket for quickly and evenly dispersing steam over the clothes being ironed without increasing to any marked degree the size or weight of the complete ironing unit.

Another object has been to provide in an ironer an ironing shoe embodying a water jacket which is so constructed and positioned with respect to the heating element in the shoe that water in the jacket can be heated to the boiling point quickly and with a minimum of delay.

Another object has been the provision of convenient means for filling the jacket with water and for draining the remaining water after the ironing has been completed. These means are constructed and arranged to prevent the filling of the jacket to a point beyond that at which steam can be safely produced.

Other and further objects and advantages will be apparent from the further and more detailed description of the invention when considered in conjunction with the drawing in which:

Figure 1 is a perspective view of the improved ironer of the invention.

Figure 2 is a sectional view along the line 2—2 Figure 1.

Figure 3 is an enlarged detailed view of the inner edge of the lip of the steam jacket particularly illustrating the disposition of the outlets for dispersing the steam over the clothes being ironed.

The details of construction of the conventional parts of the ironer illustrated form no part of the present invention. As illustrative of an ironer of a type to which the invention has application, the inventor has selected a portable, power-driven ironing machine disclosed and claimed in United States Patent No. 2,157,086 issued May 2, 1939, on the invention of William Earle Stilwell, Jr. This same construction is also illustrated and claimed as to other features in a copending ap-

lication of the said Stilwell filed March 2, 1939, as Serial No. 259,396.

In the ensuing description, the conventional elements of the ironer will be identified and described only to the extent necessary to provide a clear understanding of the relationship between the novel elements of the present invention and the elements of a conventional ironer of which the aforesaid Stilwell structure has been selected as being representative of the portable type.

Referring now to the drawing and particularly Figure 1, a portable ironer embodying the present invention is there indicated generally. The ironer includes a base 10, a cantilever bracket 11 having its pedestal portion secured to the base and a feeding roll 12 mounted on the extended arm of the bracket. The steam jacket of the invention is indicated generally at 13. The heating element which performs the dual function of heating the ironing surface of the shoe and converting to steam water positioned in the jacket is positioned on the inner side of the jacket adjacent the feed roll and is designated as 14. This heating element may be a conventional arrangement of resistance coils. A T-shaped bracket 15 is disposed against the outer surface of the steam jacket and holds the jacket and heating element releasably positioned against the roll. Leaf springs 16 which serve as guides for the articles ironed are positioned between the bracket and the jacket. The bracket 15 and the springs 16 are held together by the studs 30 which, as illustrated in Figure 2, pass completely through the steam jacket. Nuts 17 are screwed to the outer ends of the studs. At its lower end the T-shaped bracket is secured on a rock shaft 18, which shaft is arranged horizontally on the base and supported by bearing brackets 19 in which the shaft is rotatably mounted. The operating lever 20 may be removably pinned to the rock shaft and has a handle portion 21 at its outer end. The manipulation of the operating lever is effective to rock the shaft and to actuate the ironing shoe 27 into and out of contact with the roll, as desired.

The current which energizes the heating element passes through the switch box 22 and from there through the wiring 23 and the jacket 13 to the heating element. The wiring 23 may be encased in a sleeve passing through the jacket similar in construction to the sleeve 31 which encloses the stud 30. The current enters the switch through the wiring 24 which may be connected to a suitable source of power. The switch may be utilized to control the drive of the roll coincidentally with the movement of the heating element into engagement with the roll. The water intake opening may be positioned on the outer surface of the steam jacket and has been designated as 25. An outlet or discharge opening has been indicated as 26. The positioning of the inlet permits it to perform the function of an overflow valve and prevents water from being poured into the steam jacket to a higher level than that of the opening. In this way there is never a greater quantity of water in the jacket than can be quickly converted into steam. The outlet opening is utilized only when the ironing has been completed before the full supply of water has been utilized.

Certain other details of the structure are best illustrated in Figure 3. The arcuate ironing surface 27 of the shoe is positioned between the roll 12 on one side and the heating element 14

on the other. The inner surface 28 of the jacket 13 is positioned directly adjacent the outer surface of the heating element. Since no insulation is provided between the heating element 14 and the inner surface of the jacket, the heat from the element will be quickly conducted through the jacket to the water and, because of the fact that the water is closely confined in the crescent-shaped contours of the jacket, it will quickly turn to steam, rise, and pass outwardly through the apertures 29 on the lip of the jacket. As shown in Figure 3, these apertures are spaced evenly along the lip so that the steam will be distributed over the entire area of the clothes in ironing position on the roll.

The stud 30 passes through a sleeve 31 in the jacket and the heating element, and its inner end 32 is secured as by welding to the outer surface of the shoe 27. Coiled springs 33 may be interposed between the extended arms of the T-shaped bracket 15 and the leaf springs 16. This permits the jacket and heating element to be held against the roll under spring pressure but allows the shoe to be sprung away from the roll when there are irregularities in the thickness of the material being ironed.

The roll may comprise an open cylindrical drum having a padded periphery of fibrous material 34, such as cotton or felt fibers, and a cloth cover 35.

As will be apparent from the foregoing description, the operation of the device is extremely simple. Prior to the ironing operation, the jacket is filled with water up to the height of the inlet opening. Thereafter the current is turned on and the heating element commences radiating heat in both directions. By the time the heating element is sufficiently hot to permit ironing, the water in the jacket will have commenced boiling and the steam will commence escaping from the apertures 29. In fact, the escape of steam may operate as a signal that the ironing surface 27 of the shoe is sufficiently heated to be ready for use. So long as water remains in the jacket, the steam will continue to escape at a regular rate and the jacket can be refilled from time to time as desired. When steam ceases its escape from the apertures 29, the fact will be readily apparent to the operator. However, if desired, a thermostat may be utilized to register any undue heating of the ironing surface of the shoe due to the absence of water in the jacket.

As clothes are fed onto the roll, they are first subjected to a spray of steam from the apertures 29 before they are contacted by the ironing surface of the shoe. In this way, each part of each garment is thoroughly steamed prior to being ironed. The heat from the ironing surface of the shoe is sufficient to evaporate substantially all of the finely divided moisture so that as the clothes pass out on the spring leaves 16 they are substantially dry. The same result is obtained if successive ironings of one article are required.

Although a portable ironer has been illustrated as representative of a preferred embodiment of the invention, it will be apparent that the invention may be used with various other types of ironers and is not necessarily limited to this particular type.

Having described my invention, I claim:

1. In a power driven ironer of the type having a rotatable roll, an ironing element and means for supporting the roll and ironing element in cooperative relationship, a heating element positioned exterior of said ironing element and a water jacket positioned exterior of said heating

element, said water jacket having an inner surface substantially coextensive with the outer surface of the ironing element but having a lip extending outward and beyond the edge of said ironing element, the inner surface of said lip being closely adjacent the roll, said lip having apertures on its inner surface for the escape of steam from the jacket whereby articles passing over the roll will receive steam escaping from the apertures prior to engagement with the ironing element.

2. In an ironing machine, a rotatable roll, an ironing element and means for supporting the roll and ironing element in cooperative relationship, a heating element positioned exterior of the ironing element and a water jacket positioned exterior of the heating element, said water jacket having an apertured lip overhanging the roll for the application of steam to articles passing over

the roll, said heating element being recessed in the inner surface of the jacket and shielded from the lip by the ironing element to prevent the steam from contacting the heating element.

3. An ironer comprising a rotatable roll and an ironing shoe supported adjacent said roll, said shoe being of generally arcuate configuration, a water jacket disposed exteriorly of the ironing shoe and being substantially coextensive therewith, said water jacket having an apertured lip overhanging the roll for the application of steam to articles passing over the roll, and a heating element positioned between the outer wall of the shoe and the inner wall of the jacket, whereby the jacket will absorb a substantial portion of the heat generated by the element and thereby prevent over-heating of the shoe.

JOHN J. GETGEY.
